UNITED STATES PATENT OFFICE.

CHARLES P. WETHERBEE, OF BATH, MAINE.

STEAM-PACKING FOR TURBINES.

No. 911,350.

Specification of Letters Patent.

Patented Feb. 2, 1909.

Application filed June 20, 1908. Serial No. 439,560.

To all whom it may concern:

Be it known that I, CHARLES P. WETHERBEE, of Bath, in the county of Sagadahoc and State of Maine, have invented certain new and useful Improvements in Steam-Packings for Turbines, of which the following is a specification.

This invention relates to steam turbines, and consists of a system for sealing the shaft 10 stuffing-boxes or glands with steam, and maintaining a constant pressure in the seal so as to prevent steam leakage outward from the high-pressure turbines and leakage of air into the low-pressure turbines.

15 In brief, it consists of connections between the stuffing-boxes of the several members of a turbine installation so that the steam leaking from the glands of the high-pressure turbine may seal the glands of the low-pressure turbine, together with outlet and inlet connections by which the steam pressure in all the glands may be maintained at any desired point above that of the atmosphere, and kept from rising above the desired 25 point.

Of the accompanying drawings,—Figure 1 represents a plan view of a turbine installation consisting of a high-pressure and two low-pressure turbines. Fig. 2 represents an elevation of the same. Fig. 3 is a diagrammatic representation, on an enlarged scale, of the installation shown in Fig. 1. Fig. 4 represents an end elevation of the engine as seen from the forward side. Fig. 5 represents an end elevation as seen from the opposite end thereof. Fig. 6 represents a fragmentary elevation of a somewhat different layout of turbine engine, showing also the valve for admitting and relieving steam in 30 the gland connections. Fig. 7 represents a fragmentary sectional view of one end of a steam turbine, showing the shaft stuffing-box or gland. Fig. 8 represents an enlarged longitudinal section of the stuffing-box or 35 gland. Fig. 9 represents a cross-section of the same on line 9—9 of Fig. 7.

The same reference characters indicate the same parts in all the figures.

Referring to the drawings, *a* represents a 40 high-pressure turbine, and *b* and *c* represent two low-pressure turbines arranged as the same are laid out in an engine-room. The high-pressure turbine takes steam from the boiler and exhausts it into the two low- 45 pressure turbines through pipes *d* and *e*.

From the latter the steam is exhausted through the conduits *f* and *g* into the condenser *h*.

The revolving shafts of the turbines pass through stuffing boxes or glands in the ends 50 of the cylindrical casings, these stuffing-boxes being constructed as shown in Figs. 7 and 9. Each is formed as a sleeve *i* surrounding a shaft *j*, and containing packing elements. These consist of annular sharp 55 fins *k* and *l* set alternately into the interior of the sleeve and the exterior of the shaft, the edges of each fin almost touching the opposite surface. Beyond the fins the stuffing-box is formed with an annular pocket or 60 chamber *m*, and between the latter and the end of the stuffing-box is a series of snap rings *n* set into annular grooves in the cylinder and bearing against the internal surface of the sleeve. The overlapping fins form a 65 labyrinthine stuffing-box through which the steam leaks slowly into the pocket *m*, which I call the "leak-off" pocket.

The pressure tending to move the steam through the stuffing box is that of the exhaust of the turbine. In the high-pressure turbine it may be varied from vacuum to a considerable amount above the atmospheric pressure, while in the low-pressure turbines, it is always a vacuum almost as great as that 80 in the condenser. There is thus a tendency for steam to leak out of the high-pressure turbine along the shaft to the leak-off pocket, and an opposite tendency for any steam which may be supplied from an external source into the leak-off pocket of the 85 low-pressure turbine to leak therefrom along the shaft into the interior of the turbine, and thence to the condenser.

My invention consists in connecting the 90 leak-off pockets of the high and low-pressure turbines together so that the steam which is supplied to the former by leakage will pass to the latter and seal the low-pressure turbine glands so that air will not leak into the 100 turbine. For making these connections, I provide a system of piping consisting of the main pipe *o* with which connect branches *p* *q* *r* *s* *t* leading to each of the several stuffing-boxes. The connection with each leak-off 105 pocket is made through a chamber *u* beneath the stuffing-box from which passages *v* extend to the pocket. It will be readily seen that the pressure in the piping, which I term the "gland equalizer pipe," and in all the 110

leak-off pockets, will be the same, for the steam at high pressure in the pockets of the high-pressure turbine glands flows at once to the low-pressure glands and equalizes the 5 pressure.

It is necessary to maintain the pressure in the gland pockets slightly above the atmospheric pressure, so that there may be no leakage of air into the low-pressure turbines, 10 but it should be only a slight amount above the atmospheric pressure to minimize leakage beyond the snap rings n of the stuffing-boxes and loss of steam. In practice I maintain the pressure in the equalizer pipe at one 15 or two pounds above the atmosphere.

If there is not enough steam supplied by leakage from the high-pressure turbine to maintain this pressure, additional steam must be supplied from some other source, 20 such as auxiliary exhaust, a higher pressure stage of a turbine, or even boiler steam, while, if, on the contrary, the flow from the high-pressure gland is greater than the leakage into the low-pressure turbines, it is 25 necessary to relieve the excess of pressure by exhausting some of the steam into the condenser or to some stage of the turbine where the pressure is less than that to be maintained in the gland pockets and equalizer 30 pipes.

The connections for admitting and exhausting the steam to and from the pipe are best shown in Fig. 6, where w is a branch connection leading to the condenser conduit 35 f' , and x is a supply pipe from some source where pressure is greater than that desired in the gland pockets, and connected to the gland equalizer pipe. The latter is governed by a valve y , while the exhaust connection has a valve z . These valves may be 40 ordinary hand valves, spring loaded valves, or reducing or pressure-regulating valves, as desired. When properly adjusted, they serve to maintain the steam at the desired 45 pressure in all of the gland leak-off pockets, and by adjustment, the pressure in all of the glands simultaneously may be varied. A gage z' is connected to the equalizer pipe and located at the handling platform.

50 I claim:—

1. In combination with a series of steam turbines, of pressure-equalizing connections between the stuffing boxes of the several turbines.

55 2. In a steam turbine installation, consisting of a series of turbines exhausting steam at different pressures, each having shaft stuffing boxes or glands, a gland equalizer pipe connected to all the turbine stuffing 60 boxes, in which steam is maintained at a pressure slightly above that of the atmosphere.

65 3. In a steam turbine installation, consisting of a series of turbines exhausting steam at different pressures, each having a

shaft stuffing box or gland, containing packing members and provided with a pocket or chamber beyond said packing members, a gland equalizer pipe connected to the pockets or chambers of all of said stuffing boxes to maintain a uniform pressure 70 therein.

4. In a steam turbine installation, consisting of a series of turbines exhausting steam at different pressures, each having 75 shaft stuffing boxes or glands, with packing elements in said stuffing boxes, piping connecting all of the stuffing boxes together at points outside of or beyond said packing elements, with provisions for maintaining 80 steam pressure in said piping slightly above atmospheric pressure.

5. In a set of high- and low-pressure turbines having shaft stuffing boxes provided 85 with steam pockets, provisions for permitting flow of steam between the stuffing-box pockets of the several turbines to equalize the pressure therein and maintain the same in all slightly above the atmospheric pressure.

90 6. In a set of high- and low-pressure turbines having shaft stuffing boxes provided with steam pockets, provisions for permitting steam leaking into the stuffing-box pocket of the high-pressure turbine to flow 95 into the stuffing box pocket of the low-pressure turbine to maintain the pressure in the latter above the atmospheric pressure and prevent leakage of air into the low-pressure turbine.

100 7. In a set of high- and low-pressure turbines having shaft stuffing boxes provided with steam pockets, provisions for permitting steam leaking into the stuffing-box pocket of the high-pressure turbine to flow 105 into the stuffing-box pocket of the low-pressure turbine to maintain the pressure in the latter above the atmospheric pressure, together with provisions for relieving excess pressure and for making up deficiencies in the 110 supply of steam.

115 8. In the combination of high-pressure and low-pressure turbines having shaft stuffing-boxes provided with steam pockets, piping connecting the pockets of the different turbines together so that steam leaking into the pocket of the high-pressure turbine may flow into the pocket of the low-pressure turbine and seal the gland thereof.

120 9. The combination of high-pressure and low-pressure turbines having shaft stuffing boxes provided with steam pockets, piping connecting the pockets of the different turbines together so that steam leaking into the pocket of the high-pressure turbine may flow 125 into the pocket of the low-pressure turbine and seal the gland thereof, and an outlet from said piping for escape of excess of steam to permit the pressure in the pockets to be maintained at a certain maximum.

10. The combination of high-pressure and low-pressure turbines having shaft stuffing boxes provided with steam pockets, piping connecting the pockets of the different turbines together so that steam leaking into the pocket of the high-pressure turbine may flow into the pocket of the low-pressure turbine and seal the gland thereof, and a connection with said piping from a source of steam supply, by which steam, in addition to that furnished from the high-pressure pocket, may be supplied to the low-pressure pocket to maintain a sealing pressure therein above the atmospheric pressure.
11. In combination with a set of turbines having shaft stuffing boxes, an auxiliary source of steam supply, a single valve controlling admission of steam from said source, and connections for leading steam from said valve to all the stuffing boxes to provide a steam seal at a pressure regulated by the single valve.

In testimony whereof I have affixed my signature, in presence of two witnesses.

CHARLES P. WETHERBEE.
